UNITED STATES PATENT OFFICE.

LOUIS COHEN, OF WASHINGTON, DISTRICT OF COLUMBIA.

ELECTRICAL SIGNALING.

Application filed June 29, 1921. Serial No. 481,340.

To all whom it may concern:

Be it known that I, LOUIS COHEN, a citizen of the United States, residing at Washington, in the District of Columbia, have invented a certain new and useful Improvement in Electrical Signaling, of which the following is a specification.

This invention relates to the art of electrical signaling, particularly, receiving radio signals, and a system for use in practicing the same.

The object of the present invention is to eliminate interferences in the reception of radio signals and thus insure greater reliability in radio communication.

It is well known that in the present practice of radio signaling, interferences from other stations are not entirely eliminated. When the difference in the frequencies between the signals to be received and the interfering signals is small, the various tuning arrangements now generally used in present practice are not effective in completely eliminating the interference effects. In this invention, a new method is used by which a higher degree of selectivity is obtained.

In carrying out the invention, the incoming signals are acted upon by local oscillations which combine with them producing beats. The beat frequency current is then impressed upon a Wheatstone bridge, the constants of the arms of which are so adjusted as to produce zero potential across the bridging arm for the current of the beat frequency, and hence no current flow in it. The indicating instrument is coupled to two arms of the bridge and also to the bridging arms. By properly adjusting the couplings in the matter of direction and magnitude, a condition is obtained where the interference effects are balanced out, and the indicating instrument responds only to the signals which are to be received.

The principle of operation can be better understood by reference to the accompanying diagrammatic figure which shows the typical embodiment of the invention, and forms part of this specification.

The antenna system shown in the drawing consists of an antenna 1, loading inductance 2, and ground 3. The secondary circuit 4, 5, is coupled to the antenna system and has associated with it, a three electrode vacuum tube 6 with a regenerative coupling coil 7, for producing local oscillations effect-

ing beats with the incoming signals. The beat frequency current flowing in plate circuit 9 is impressed through the secondary 10 of transformer 8 and the Wheatstone bridge at the points 11, 12. The four arms of the bridge, *a*, *b*, *c*, *d*, consisting of inductances and capacities 13, 14; 15, 16; 17, 18; 19, 20; respectively, are so adjusted as to obtain an exact balance for the beat frequency current on the bridging arm 21, hence no current flow in it. The beat frequency current, however, in passing through the bridge arms *b* and *d*, induces E. M. F.'s in the secondaries 24, 26, and by properly connecting the secondaries 24, 26 the effects are made additive and thus, set up a current flow in the circuit 22, 24, 28, 26 which affects the indicator 28. For currents of different frequencies the bridge is no longer balanced and there will be, therefore, a current flow in the bridging arm 21. By properly adjusting the transformers 23, 25 and 27 in respect to magnitude and direction, a condition is obtained whereby the E. M. F.'s induced in the secondary 22 of transformer 23 neutralize the resultant E. M. F.'s induced in the secondaries 24 and 26 of transformers 25 and 27 respectively, and therefore no current flow in the circuit 22, 24, 28, 26, and hence no effect on the indicator 28.

We may take the following example in illustrating the operation of this invention. Suppose the bridge arms of the Wheatstone bridge are adjusted for balance at the frequency of 500. If it is desired to receive a signal at a frequency of 50,000, the local oscillator is adjusted to produce oscillations of frequencies either 50,500 or 49,500, so that in either case a beat frequency of 500 is obtained, and for that beat frequency current the bridge is completely balanced, no current flow in the bridging arm 21, and hence the E. M. F.'s induced in the secondaries of transformers 25 and 27 set up a current flow in the indicator circuit affecting the indicator. If, however, an interfering signal of slightly different frequency, say 50,100, acts on the antenna, the beats produced with the local oscillations in this case with be either 400 or 600, and in either case the balance of the bridge is upset, setting up a current flow in the bridging arm 21 which may be made, by properly adjusting its secondary, to neutralize the E. M. F.'s induced in the secondaries of the other two transformers 25 and 27, and hence render the indi-

cator circuit free from the disturbing effect of the interfering signal. It is seen, therefore, that for this arrangement the interference effects for such a small difference of frequency as 1 in 50,000 or one-fifth of one per cent, may be completely eliminated.

It is obvious that various modifications of the circuit arrangement may be made without departing from the spirit of the invention. Any method for generating local oscillations, or any means employed to rectify the high frequency oscillations clearly comes within the scope of this invention. The diagram and description given here shows only a typical embodiment of the invention illustrating the underlying principles governing its operation.

I claim:

1. An improvement in radio signaling, comprising an antenna system and secondary oscillating circuit coupled to the said antenna system, means for generating local oscillations in said secondary oscillating circuit, said local oscillations combining with the high frequency currents flowing in the antenna and producing beats, said beats current being delivered to a Wheatstone bridge, an indicator being connected in a circuit which is electrically associated with two arms and the bridging arm of the said Wheatstone bridge.

2. Radio signaling apparatus comprising an antenna system and secondary oscillating circuit coupled to the said antenna system, a three electrode vacuum tube detector including a regenerative coil operatively associated with the secondary oscillating circuit for producing oscillations in the said secondary circuit, said oscillations combining with the incoming signals and producing beats, said beat current being delivered through a transformer to a Wheatstone bridge, the arms of said Wheatstone bridge being adjusted to obtain a balance on the bridging arm; an indicator being connected to a circuit which is coupled to two arms of the bridge and the bridging arm of the said Wheatstone bridge.

3. An improvement in radio signaling, comprising an antenna system and secondary oscillating circuit coupled to the said antenna system, means for generating local oscillations in said secondary oscillating circuit, said local oscillations combining with

the high frequency currents flowing in the antenna and producing beats, said beat current being delivered to a Wheatstone bridge, an indicator being connected to a circuit which is coupled to two arms of the bridge and the bridging arm of the said Wheatstone bridge.

4. An improvement in radio signaling, comprising an antenna system and secondary oscillating circuit coupled to the said antenna system, means for generating local oscillations in said secondary oscillating circuit, said local oscillations combining with the high frequency currents flowing in the antenna and producing beats, said beat current being delivered through a transformer to a Wheatstone bridge, an indicator being connected to a circuit which is coupled to two arms of the bridge and the bridging arm of the said Wheatstone bridge.

5. An improvement in radio signaling, comprising an antenna system and secondary oscillating circuit coupled to the said antenna system, means for generating local oscillations in said secondary oscillating circuit, said local oscillations combining with the high frequency signal currents flowing in the antenna and producing beats, said beat currents being delivered through a transformer to a Wheatstone bridge, the arms of said Wheatstone bridge being adjusted to obtain a balance on the bridging arm for the said beat currents; an indicator being connected to a circuit which is coupled to two arms of the bridge and the bridging arm of the said Wheatstone bridge.

6. Radio signaling apparatus comprising an antenna system and secondary oscillating circuit coupled to the said antenna system, a three electrode vacuum tube detector including a regenerative coil operatively associated with said secondary oscillating circuit for producing oscillations in the said secondary circuit, said oscillations combining with the incoming signals and producing beats, a Wheatstone bridge for receiving the beat current, the arms of said Wheatstone bridge being adjusted to obtain a balance on the bridging arm; and an indicator connected in a circuit coupled to two arms of the bridge and the bridging arm of the said Wheatstone bridge.

LOUIS COHEN.
